UNITED STATES PATENT OFFICE.

DONALD NOBLE, OF LEEDS, ENGLAND.

PORTABLE PUMPING APPARATUS.

SPECIFICATION forming part of Letters Patent No. 519,871, dated May 15, 1894.

Application filed February 23, 1893. Serial No. 463,423. (No model.) Patented in England November 24, 1891 No. 20,434; in France September 14, 1892, No. 214,211; in Belgium September 14, 1892, No. 101,370, and in Canada December 12, 1892 No. 41,191.

To all whom it may concern:

Be it known that I, DONALD NOBLE, a subject of the Queen of Great Britain, residing at Leeds, in the county of York, England, have invented new and useful Improvements in Portable Pumping Apparatus, (for which I have obtained Letters Patent in Great Britain November 24, 1891, No. 20,434; in France September 14, 1892, No. 214,211; in Belgium September 14, 1892, No. 101,370, and in Canada December 12, 1892, No. 41,191,) of which the following is a specification.

This invention relates to improvements in portable or other pumping apparatus, and it is applicable for use in connection with baths or trays that may be removed from one room to another, as well as with baths that are a fixture. It may also be used for washing or bathing dogs, horses or other animals, carriages, windows, watering or sprinkling flowers, plants, trees, and the like, or for extinguishing fires and for other similar purposes. Its object is to provide a light, cheap, simple, effective, and portable or other single or double acting pumping apparatus capable of being worked by the heel of one foot or both feet of the operator for raising the water from a bucket, receptacle, or the like on to the operator, or any other desired object or thing and at the same time permitting of the operator having the free use of both hands (when working the apparatus with the feet) for washing purposes or for directing or controlling the supply of water.

In the accompanying drawings, Figure 1 is a front elevation with one of the sides of the platform or casing removed, of a pumping apparatus embodying my improvements. Fig. 2 is a plan of the same, looking at the top. Fig. 3 is an elevation of the apparatus shown in Fig. 1, with one of the end pieces removed. Fig. 4 is a sectional elevation of the cylinders, pistons and the valve box. Figs. 5 and 6 are respectively a sectional elevation and plan of the valve box. Figs. 7 and 8 are respectively a front elevation and an end elevation of the mechanism for throwing the pedals into and out of operation.

The platform or casing A, may be made of any suitable material and of any convenient

size or dimensions. It is divided into two compartments a^x and a' . The compartment a^x is open at the top, while the compartment a' is preferably open at the bottom or it may be closed when desired by a lid X, as indicated in Fig. 3. The top of compartment a' may be closed by a lid X'. In compartment a^x are fixed the pumping mechanism, while the bathing or toilet requisites may be packed away in compartment a' . By covering the compartment a' as shown water is prevented from entering therein.

B B' are single acting pump barrels fixed vertically within compartment a^x and arranged so that the pistons H H', which reciprocate therein, shall be capable of making a stroke the full length of the barrel, that is they are capable of being raised until their upper surface is level with the top of the barrels.

The pedals I I' consisting of skeleton metal framing lined with wood, are attached at their toes or ends farthest from the pump barrels to the platform A at I⁴ I⁵ by means of a wide joint or hinge so as to prevent as much as possible any lateral movement at the front end of the pedals, thereby enabling the pistons to work evenly.

In order that the operator may stand on the pedals with his feet at an angle to each other and still be able to impart a direct and even pressure to the pistons, that is to cause them to work perfectly evenly in the pump barrels, the pedals are made much wider at the toes than at the heels.

The outer ends of the pedals I I' are arranged to bear upon the double ended lever I¹¹ which in turn is jointed at or about its center between cranks L L^x mounted by trunnions L' L² in bearings L³ L⁴ formed for their reception respectively in the bracket I⁴ and on the valve box J. To the trunnion L' is fixed on the outside of the platform A a lever L⁵ which is employed for raising when turned to the right hand, the lever I¹¹ with its center l of oscillation above that of the trunnions into the position shown at Fig. 1, that is the end I²⁰ of the lever will be raised while end I²¹ will be depressed thereby placing the pedals in position for actuating the pistons.

But when the lever L⁵ is turned to the left hand with

the center of oscillation below that of the trunnions then the lever I^{11} may be passed below the upper edge of compartment a^x , and both the pedals closed on to the top of the platform for packing purposes. The ends I^{20} I^{21} of lever I^{11} are armed with runners $i^x i^{xx}$ as shown on which the under side of the pedals rest. Or when preferred the ends of lever I^{11} may be connected to the under side 10 of the pedals by a universal or other joint. Spring catches $M M'$ are employed for retaining lever L^5 in position.

The pistons $H H'$ are connected to the 15 pedals $I I'$ by means of links $K K'$ which are jointed at their respective ends to the said parts, that is link K is attached to the pedal I and piston H at $K^2 K^3$; and link K' is attached to pedal I' and piston H' at $K^4 K^5$.

The pump barrels $B B'$ are connected at 20 their lower ends by the pipes $J^2 J^3$ to the valve box J . The valve box J is divided into two compartments $J^x J^{xx}$ communicating with the same inlet and outlet in which the valves $c^8 c^9 c^{10} c^{11}$ are arranged to work as described. 25 Connected with the top of the valve box J is a tube J^4 which is bent and carried down within a second tube E (placed parallel with the valve box J and arranged to communicate with and to form part of the air vessel 30 F) to within a short distance of the line of the bottom of the valve box. The air vessel F passes round the side and two ends of compartment a^x and it is also employed for strengthening the platform. The outlet tube 35 G is also passed down the tube E to the level of the bottom of tube J^4 . Water is admitted to the valve box J through pipe J^5 . To the inlet pipe J^5 and outlet tube G may be respectively attached pieces of flexible tubing 40 of suitable lengths, that for the inlet being armed with an ordinary nozzle, and the outlet with any kind of self-feeding brush, or rose, or nozzle through which water forced by the herein described pumping apparatus may 45 be employed and used therewith.

N is a handle attached to the platform for carrying purposes.

The mode of operating the pumping apparatus is as follows:—The lever L^5 having been 50 turned to the right hand (and secured in position by spring catch M) for placing the pistons $H H'$ in position, the nozzle on the flexible tube attached to the inlet pipe J^5 is then immersed in a bucket of water. Motion for 55 actuating the pistons is imparted by the heels of the operator's feet as he balances himself upon the pedals. On pedal I being depressed pedal I' will be raised by end I^{21} of lever I^{11} and by means of the vacuum formed (by the 60 receding piston H') in the compartment H^{10} of pump barrel B' (valves $c^{10} c^{11}$ being then opened and valves $c^8 c^9$ closed) water will be drawn from the bucket through flexible tube, inlet J^5 into valve box J through valve c^{11} pipe 65 J^3 into compartment H^{10} . On the depression of pedal I' water thus drawn into the compartment

H^{10} will be ejected there from (the valves being automatically altered into the position shown at Fig. 4 that is valves $c^8 c^9$ will now be opened and valves $c^{10} c^{11}$ closed) by the 70 piston H' . The water from compartment H^{10} passes through pipe J^3 , valve c^8 into pipe J^4 when it is carried down to the bottom of the tube E (which forms a part of the air vessel F) and gradually rises in this tube until a sufficient supply of water has been admitted from both pump barrels to sufficiently compress the air therein. When this has been done the water will be forced up tube G and delivered through a brush or the like on the 80 flexible pipe (attached to tube G) in a continuous stream. While the water is being forced from compartment H^{10} into pipe E as described, water is simultaneously being drawn from the bucket into compartment H^9 85 of pump barrel B through inlet pipe J^5 , valve box J , valve c^9 and pipe J^2 . On the depression of pedal I and on the descent of piston H (the valves being then in the first mentioned order, namely $c^{10} c^{11}$ open and $c^8 c^9$ 90 closed) the water in compartment H^9 will be forced through pipe J^2 , valve c^{10} , pipe J^4 , tube E , and out through tube G as already described. At the same time water will be drawn into the compartment H^{10} as previously 95 described. By this means water may be drawn into one compartment simultaneously with the ejection of the water from the compartment of the other barrel the valves automatically adjusting themselves therefor. 100

Having now particularly described and ascertained the nature of this said invention and in what manner the same is to be performed, I declare that what I claim is—

1. The combination of a platform or casing, 105 a pair of pedals hinged thereto at their toe ends, cylinders within the casing, pistons reciprocating therein, link connections between the pedals and the pistons, inlet and outlet ports or passages from the cylinders, valve mechanism controlling the flow of water, and a lever pivoted at its center to the platform or casing and having rollers on its opposite ends adapted to engage with the under sides of the pedals. 115

2. The combination of the platform or casing divided into two compartments, a pair of pedals hinged at their toe ends to the casing, cylinders mounted in one of the compartments, pistons reciprocating in the cylinders, 120 link connections between the heel ends of the pedals and the pistons, ports or passages for fluid entering and leaving the cylinders, valve mechanism controlling these passages, and locking devices for holding the heel ends of 125 the pedals depressed.

3. The combination of a platform or casing, 130 pedals hinged thereto, cylinders within the casing, pistons reciprocating therein and operatively connected with the pedals, entrance and exit ports or passages having valve mechanism for controlling the flow of water there-

in, a pivoted lever with the ends of which the
pedals are adapted to engage, crank arms on
which the lever is pivoted, trunnions for said
crank arms below the axis about which the
5 lever moves on the crank arms, a lever or
handle for turning the crank arms and means
for locking the handle.

In testimony whereof I have hereunto signed
my name to this specification in presence of
two subscribing witnesses.
